VANITY SINK

Donald G. Lauer, Elizabeth, N.J., Cooper C. Woodring, Plandome, N.Y., and Joseph Anthony Rinaldi, Fort Lee, N.J., assignors to J. C. Penney Company, Inc., New York, N.Y.

Filed Jan. 6, 1971, Ser. No. 104,530

Term of patent 14 years

Int. Cl. D23—02

U.S. Cl. D23—58

FIG. 1

FIG. 2

FIG. 3

FIG. 4

FIG. 5

FIG. 1 is a perspective view of a vanity sink, showing our new design;

FIG. 2 is a top plan view thereof;

FIG. 3 is a front elevational view thereof, partially cut away for convenience of illustration;

FIG. 4 is an elevational view taken from one side thereof, the opposite side being a mirror image of the side shown; and

FIG. 5 is a rear elevational view thereof.

We claim:

The ornamental design for a vanity sink, substantially as shown and described.
